UNITED STATES PATENT OFFICE.

PATRICK J. HUSSEY, OF NEW YORK, N. Y.

VALVE.

1,414,416.

Specification of Letters Patent.

Patented May 2, 1922.

Application filed March 24, 1921. Serial No. 455,083.

To all whom it may concern:

Be it known that I, PATRICK J. HUSSEY, a citizen of the United States, and resident of the city of New York, borough of Manhattan, county of New York, and State of New York, have invented a new and Improved Valve, of which the following is a full, clear, and exact description.

In connection with valves, and more particularly such valves as utilize a ball body, it is well appreciated that difficulty has been experienced, incident to the valve chattering, particularly when the same has become worn, or when low pressure is encountered.

Furthermore, the hemispherical body of the valves, as heretofore used, had resulted in the production of a fluid jet which was divided, this being objectionable for a number of well known reasons.

Also in most types of ball controlled valves, the objection has been noted that the flow is limited, incident to the fact that the valve seat opening is restricted in size, so as to be capable of efficiently co-acting with the bell constituting the valve.

With this in mind, I have constructed a valve in which any objection incident to chatter will be avoided, and by means of which the jet fluid discharge from the valve will be solid, aside from the fact that the size of the jet will be only limited by the cross sectional area of the intake and discharge openings, of the valve.

Further objects of my invention will appear in the subsequent specification, taken in connection with the accompanying drawings, which latter present one practical embodiment of the same, and in which;

Figure 1 is a sectional side view of a valve constructed in accordance with my invention, and

Figure 2 is a sectional transverse view taken along the line 2—2 and looking in the direction of the arrows in Figure 1.

Figure 3 is a plan view of the packing box cap, and

Figure 4 is a sectional plan view taken along the line 4—4 and looking in the direction of the arrows in Fig. 1.

Primarily it will be noted that in the embodiment illustrated, I have shown my valve as forming part of a faucet, but it is to be appreciated that my invention is not necessarily limited to this adaptation.

Furthermore, the valve housing 5 may be of any desired type and a packing box cap

6, hereinafter more fully described, is associated with the same, it being also noted that the handle 7 and stem 8 may be of any customary construction.

Contrary to the conventional construction however, it will be noted that the valve seat 9 within the housing 5 is of an area substantially equivalent to the intake and discharge openings of the housing thus overcoming any objection incident to the jets of fluid being restricted in size.

Also the ball 10 co-operating with the seat 9 is obviously of a greater diameter than the seat, and consequently is also larger than the intake and discharge openings forming a part of the housing. Thus any danger of the ball becoming wedged within the body of the housing is eliminated, it being only possible to effect a removal of the ball 75 by disengaging the packing box 6.

With a view of avoiding a dividing of the jet discharge from the outlet opening of the valve, it will be noted that I subdivide the discharge opening 11 within the 80 housing by means of a bar 12 thus forming a cage for the ball 10, and it is thus to be noted that the bar 12 will cause a convergence of the particles of fluid forming the jet, thereby to produce a solid jet which is discharged from the outlet opening of the housing 5.

To now provide means which will serve to eliminate a chatter of the parts upon the same becoming worn, or incident to low 90 pressure, it will primarily be noted that, due to the structure aforescribed, that a movement of the ball 10 is limited to motion directly away from or towards the seat 9, thus overcoming any difficulty in this connection.

Furthermore, the packing box cap 6 is extended, as has been indicated by the reference numeral 13, and this extended portion is formed with screw threads 14 permitting of a tightening nut 15 being mounted thereon. Also it will be seen that the extended portion 13 is split, as has been indicated by the reference numeral 16, and that the body of the same is tapered. Thus, upon the nut 15 being tightened, it will be seen that the 105 parts constituting the upper portion of the cap 6 will be caused to contract, whereby to firmly embrace the stem 8.

Also the cap 6 is formed in the usual manner with a bore, which accommodates the 110 stem 8, and this bore is screw-threaded so that a co-operation with the screw threads

17 of the spindle may be effected, it being noted that these latter screw threads terminate at a point well above the interior of the housing 5, and that suitable gaskets 18 5 may be interposed between the housing 5 and cap 6 to effectually preclude the seepage of any fluid from the housing.

Thus I also provide a packing box ideally adapted to be utilized in combination with 10 a valve of the structure described, and which will co-operate with the same to effectually prevent any chattering of the parts incident to the reasons named.

Thus I have provided a valve which will 15 incorporate all of the advantages of a ball valve in that the only portion of the entire valve upon which any perceptible wear takes place is the inner end of the stem 8, but it will be noted that by means of my improved 20 construction that the disadvantages heretofore associated with a ball valve are eliminated as aforesaid, and it will be appreciated that obviously numerous modifications of structure might readily be resorted 25 to without in the least departing from the

spirit of my invention, which I claim as follows:

1. A valve, including a housing, a cap secured to said housing, an extended portion forming a part of said cap, said extended portion being tapered and formed of a plurality of sections, a nut adapted to embrace said extended portion, and a screw threaded valve stem adapted to extend through a screw threaded bore in said extended portion. 35

2. A valve, including a housing, a cap secured to said housing, gaskets interposed between said cap and housing, an extended portion forming a part of said cap, said extended portion being formed of a plurality 40 of sections, and being tapered throughout its entire length, a valve stem extending through a bore in said cap, the extended portion of said cap being formed with screw threads and a nut adapted to encircle said 45 extended portion and to be mounted upon said screw threads so as to cause said extended portion to firmly embrace said stem.

PATRICK J. HUSSEY.
